FIG. 4

UNITED STATES PATENT OFFICE

WILLARD M. COFFIELD AND THOMAS C. MOORE, OF LITTLE ROCK, ARKANSAS

STEAM FAN DRIER

Application filed January 3, 1928. Serial No. 244,128.

This invention relates to improvements in steam fan driers, and has for one of its principal objects the provision of a drier particularly adapted to be used in cleaning establishments for drying operations and the like on clothing and similar articles.

One of the important objects of this invention is the provision, in a fan drying apparatus, of means for injecting steam, either live or super-heated, into the current of air caused by the fan whereby garments and the like may be steamed for accomplishing of certain results thereon.

Another important object of this invention is to provide a machine for use by cleaners and dyers which will save from twenty-five to seventy-five per cent of hand finishing, and the operation of which is very simple and easy.

Another and still further important object of the invention is to provide a device which will economically and efficiently handle garments which have been dyed and rinsed even while wet, and which will also do a considerable portion of the necessary finishing work on any garment such as a dress which has been dry-cleaned, wet-cleaned or dyed.

Other and further important objects of the invention will be apparent from the disclosures in the accompanying drawings and following specification.

The invention, in a preferred form, is illustrated in the drawings and hereinafter more fully described.

In the drawings:

Figure 1 is a side elevation of the improved fan drier of this invention showing a garment applied thereto.

Figure 2 is a top plan view of the device.

Figure 3 is a front elevation.

Figure 4 is a detail view illustrating the dress clamping elements and the safety screen for preventing garments from falling into the machine.

Figure 5 is a detail view, partly in section, showing the means for supporting the garments in proper position.

As shown in the drawings:

The reference numeral 10 indicates generally the casing of the improved machine of

this invention, which may be of any suitable size, but which preferably is approximately four and one-half feet in circumference. This casing is a hollow cylinder as best shown in Figure 3, and terminates in a spout or nozzle 12, which is curved upwardly terminating in an opening in a horizontal plane as best shown in Figure 1.

Mounted in the casing 10 is a fan or the like comprising a series of blades 14 driven by a motor 16, the motor in turn being controlled by a suitable switch. The fan blades are so arranged that air enters the casing 10 adjacent to the motor 16 and is forced upwardly and outwardly through the spout 12.

The motor itself is positioned on suitable standards 18 which are continued to form further supports 20, which form the base of the apparatus and the means by which it may be secured in position.

Arranged about the periphery of the upper edge of the spout 12 is a series of clamping elements comprising fixed uprights 22 surmounted by horizontal clamping bars 24 preferably covered with rubber or the like so as to protect the material of the garments. Adapted to co-operate with these clamping bars 24 are complementary clamping bars 26, also suitably covered by means of rubber tubing or the like, and which in turn are mounted on uprights 28 pivoted to the spout 12 at 30 and terminating in operating handles 32. A coil spring or the like 34 is positioned around the upper edge of the spout 12 and mounted in suitable depressions 36 in the elements 28-32 whereby these clamping levers with their attached clamping bars 26 are normally maintained in operative gripping relation with the clamping bars 24. The method of attaching a garment or the like 40 by means of its lower hem to the upper edge of the spout 12 will be evident.

Mounted on the top of the casing 10 is an upwardly extending overhanging supporting arm 42 which is composed of hollow tubing or the like, and which has positioned therein a slidible weight 44 as shown in Figure 5, supported by means of a wire or chain 46. This in turn terminates in a ring 48 attached to the other end of the 100

wire at the outer opening of the tube 42. The hook 50 of a dress hanger 52 is adapted to be placed in the ring 48 and a pull of the dress hanger will, by tension on the wire 46, raise the weight 44. When the lower hem or edge of the dress is mounted in the clamps 24-26, the weight 44 will act to support the dress in an upright position over the opening of the nozzle 12. A screen or the like 60 is placed across the upper opening of this spout 12 so as to eliminate any possibilities of the dress being accidentally dropped into the device.

Mounted adjacent the lower forward end 15 of the casing 10 is a steam pipe 62 terminating in a nozzle 64 controlled by means of a valve 66. The nozzle 64 is swivelly mounted in the end of the pipe 62 and is provided with an adjacent handle 68 whereby the direction of the stream of steam from the nozzle 64 may be changed with respect to the interior of the casing 10 and the fan blades 14.

In completing the operation of cleaning and dyeing a dress or other garment, a very 25 large percentage of hand-finishing can be eliminated by the use of this apparatus. The garment is simply placed on the hanger 52 and hung in the ring 48. The bottom is then fastened with the catches 26 after which 30 steam from the nozzle 64 is allowed to enter the casing 10 for one or two seconds by manipulation of the valve 66. This is done while the fan is not running after which the steam is cut off, the current applied to the 35 motor 16, and the fan will then complete the operation. Dresses from six inches long or even shorter up to approximately six feet in length can be readily handled with this machine as it automatically adjusts itself to 40 the height of the garment by means of the weight 44.

We are aware that many changes may be made and numerous details of construction varied throughout a wide range without departing from the principles of this invention, and we therefore do not purpose to limit the patent granted herein otherwise than as necessitated by the prior art.

We claim as our invention:

50 A fan drier comprising a casing, fan blades in the casing, a motor for rotating the blades, a spout extending from the casing, and means for supporting a garment at the end of said spout, said means comprising a support and 55 tension means in the support for automatically maintaining the garment in an upright position, said tension means comprising a weight slidable in the support, a supporting wire for the weight and means at the 60 further end of said supporting wire for attaching a garment thereto, and means adjacent the upper end of the spout for clamping the lower edge of the garment, said means comprising manually operated spring clamps, 65 and a single spring for the clamps, said

spring surrounding the circumference of the spout and positioned against the movable arms of all of said clamps.

In testimony whereof we affix our signatures.

WILLARD M. COFFIELD. 70
THOMAS C. MOORE.
